(57) **CLAIM**

The ornamental design for an oral-motor pharyngeal muscle exerciser, as shown and described.

DESCRIPTION

FIG. 1 is a top perspective view of an oral-motor pharyngeal muscle exerciser in accordance with the present design; FIG. 2 is a bottom perspective view of the oral-motor pharyngeal muscle exerciser;

FIG. 3 is a front view of the oral-motor pharyngeal muscle exerciser;

FIG. 4 is a rear view of the oral-motor pharyngeal muscle exerciser;

FIG. 5 is a first side view of the oral-motor pharyngeal muscle exerciser taken ninety degrees from the front view;

FIG. 6 is a second side view of the oral-motor pharyngeal muscle exerciser taken one hundred and eighty degrees from the first side view;

FIG. 7 is a top view of the oral-motor pharyngeal muscle exerciser; and,

FIG. 8 is a bottom view of the oral-motor pharyngeal muscle exerciser.

Any broken lines in the drawings represent portions of the oral-motor pharyngeal muscle exerciser that form no part of the claimed design.

1 Claim, 4 Drawing Sheets
